Fred L. Riseler

INVENTOR:
John M. Johnson
BY
F. G. Fischer,
ATTORNEY.

UNITED STATES PATENT OFFICE.

JOHN M. JOHNSON, OF KANSAS CITY, MISSOURI, ASSIGNOR TO THE UNITED STATES AUTOMATIC FIRE ALARM COMPANY, A CORPORATION OF MISSOURI.

CIRCUIT CONTROLLER.

Application filed October 17, 1921. Serial No. 508,257.

My invention relates to circuit controllers and consists of novel means which can be used to advantage for either opening or closing electric circuits of different descriptions.

In the accompanying drawings, I have shown the device arranged to be actuated by the valve of a sprinkler system, so that in case said valve should be closed surreptitiously to shut off the water supply, my device will cause an alarm to be automatically turned in.

The electric circuit may be a local one, or it may be extended to headquarters as shown in the accompanying drawings, in which:

Fig. 1 is a side elevation of a valve partly in section with my device connected thereto.

Fig. 2 is a plan view of the device referred from its case.

Fig. 3 is a side elevation partly in section of the device.

Fig. 4 is a vertical cross section taken on line IV—IV of Fig. 3.

Referring now in detail to the various parts, 2 designates the supply pipe of a sprinkler system.

7 designates circuit wires which are connected to a pair of contacts 8, spaced apart 30 and constituting a portion of the circuit controller.

The supply pipe 2 of the sprinkler system is equipped with a valve 10 having an elongated stem 12 equipped with a hand wheel 14, which is threaded upon said stem 12 and adapted to move the same longitudinally in either direction to open or close the valve.

16 designates a protective case in which my circuit controller is mounted, said case being secured to the valve 10 by a yoke 18. The case 16 has an opening 17 at one end to admit the threaded valve stem 12, as shown on Fig. 1.

45 My device includes a frame 20 which is secured within the case 16 and provided at one end with the contacts 8, which are insulated from said case as disclosed by Figs. 2 to 4, inclusive.

50 A rod 22 is slidably mounted in the frame 20 and equipped with an insulator 24 upon

which a conductor 26 is fixedly mounted. The outer portions of the insulator 24 and the conductor 26 are of the same diameter in order to slide between the contacts 8 to alternately open and close the circuit 7, as will hereinafter appear.

The rod 22 is connected by a transverse member 28 to a plunger 30, which like said rod 22 is slidably mounted in the frame 20. The plunger 30 is equipped with a coil spring 32, which is interposed between one end of the frame 20 and the transverse member 28 to move said plunger 30 and the rod 22 to the left as disclosed by Figs. 2 and 3.

The plunger 30 is provided at one end with a fixedly-mounted, depending member 34, the lower end of which is arranged in the path of the valve stem 12, so that when said stem is moved to the right, Fig. 1, to open the valve 10, said stem 12 will engage and move the depending member 34 to the right and cause it, through the intervening connections, to move the conductor 26 into engagement with the contacts 8 to hold the circuit 7 closed.

With the parts constructed and arranged as shown and described it is apparent that should the valve 10 be closed and thus render the sprinkler system inoperative for lack of water, the stem 12 will move to the left in closing the valve and away from the member 34, thus allowing the spring 32 to act and interrupt the circuit by moving the insulator 24 between the contacts 8.

From the foregoing description taken in connection with the drawings it is apparent that I have provided a circuit controller which is well adapted for use in connection with sprinkler systems. However, I do not wish to be understood as restricting myself to this particular use, but reserve the right to use the invention wherever it may be employed to advantage, and I reserve the right to make such other changes in the construction, combination and arrangement of parts as properly fall within the spirit and scope of the claims.

Having thus described my invention, what I claim and desire to secure by Letters Patent, is:

1. In combination with a valve having a movable stem projecting therefrom, a case supported by said valve and into which the movable valve stem extends, contacts spaced apart within said case, a conductor arranged to engage and disengage said contacts, a plunger for actuating said conductor, a member arranged to abut the end of the valve-stem when the valve is open and fixed to the plunger to cause the same to hold the conductor in engagement with the contacts, spring means for moving the plunger in a direction to cause the conductor to pass out of engagement with the contacts when the valve is closed. 5

30

2. In combination with a valve having a movable stem projecting therefrom, a case

supported by said valve and into which the movable valve stem extends, contacts spaced apart within said case, a conductor arranged to engage and disengage said contacts, a plunger for actuating said conductor, a member arranged to abut the end of the valve-stem when the valve is open and fixed to the plunger to cause the same to hold the conductor in engagement with the contacts, spring means for moving the plunger in a direction to cause the conductor to pass out of engagement with the contacts when the valve is closed, and a circuit connected to the contacts.

In testimony whereof I affix my signature.

JOHN M. JOHNSON.
